UNITED STATES PATENT OFFICE.

WILLIAM F. BERMAN, OF CHICAGO, ILLINOIS.

DESIGN FOR A BOTTLE.

SPECIFICATION forming part of Design No. 35,510, dated December 31, 1901.

Application filed December 5, 1901. Serial No. 84,758. Term of patent 14 years.

To all whom it may concern:

Be it known that I, WILLIAM F. BERMAN, residing in the city of Chicago, county of Cook, and State of Illinois, have invented and produced a new and original Design for a Bottle, of which the following is a specification, reference being had to the accompanying drawing, forming a part hereof.

Said drawing illustrates in perspective a bottle made in accordance with my novel design.

A bottle made in accordance with my novel design consists of a body which is rectangular in horizontal section and having flat side, end, and bottom walls. The top wall consists of two oppositely-inclined halves or parts which meet in the plane of the longitudinal center of the body of the bottle. The end and the lower side margins of the inclined parts of the top wall extend beyond the end and side walls, respectively, of the body part of the bottle, and the upper ends of the end walls are tapered to conform to the inclination of the parts of the top wall. The upper surfaces of the parts or halves of said top wall are divided into a plurality of longitudinal parallel sections, which are offset with respect to each other, and each of said longitudinal sections is subdivided by a plurality of transverse lines or channels, the transverse lines of adjacent longitudinal sections being located out of line with respect to each other. Rising from the apex of the top wall at the transverse center thereof is a hollow neck, which is open at its top and the base of which is

formed to overlap the oppositely-inclined parts of said top wall a short distance on each side of the apex thereof. The lower part of said neck is rectangular in cross-section, and the top thereof is rounded or cylindric. Between the upper rounded part of the neck and the lower square part thereof is a generally rectangular horizontal flange surrounding the neck, and the top of said neck is mounted by a circular flange. The angles or corners at the intersections of the plane flat surfaces of the body and neck of the bottle are somewhat rounded in the manner shown, thereby avoiding sharp angular corners.

The main or characteristic features of my novel design consist of the rectangular body having plane side, end, and bottom walls and rounded corners, a top wall consisting of oppositely-inclined parts or halves marked or figured in the manner described, and the hollow neck rising from the apex of said top wall, the bottom of which is rectangular and the top of which is rounded or cylindric.

Having now described my novel design, what I claim is—

The design for a bottle substantially as herein shown and described.

In witness whereof I hereunto set my hand at Chicago, Illinois, this 21st day of October, A. D. 1901.

WILLIAM F. BERMAN.
